UNITED STATES PATENT OFFICE.

MAX A. MARSCHNER, OF WILLOW GROVE, PENNSYLVANIA.

METHOD OF MAKING FULL-FASHIONED HOSIERY AND PRODUCT THEREOF.

Application filed December 7, 1925. Serial No. 73,627.

My invention relates to a new and useful method of making full fashioned hosiery and the product thereof wherein, a novel method of narrowing is employed in shaping the hose in such a way as to eliminate from view, on the finished product, the unsightly narrowing points, which otherwise appear upon this class of hosiery as a result of the usual narrowing operation.

10 In making full fashioned or flat knitted hosiery, heretofore, it has been the practice to provide at each end of the hose, that is, along the edges of the hose in the flat condition, a relatively large number of narrowing needles, to wit, in the neighborhood of eighteen. The narrowing operation along each edge of the hose being thus performed by a relatively large number of narrowing needles, the series of narrowing points, over 15 20 the portion of the hose which was narrowed or reduced in width, being spaced a considerable distance from the edges of the hose.

In knitting full fashioned hosiery of the finer grades, particularly, of the finer grades of silk, such as, for instance, the chiffon hosiery, great difficulty has been experienced and great loss has been incurred due to the frequent breaking of a stitch or thread at the 25 30 narrowing points, thereby causing runs at that particular line of knitting and hence, so damaging the product as to materially depreciate its value and to make "seconds" and "thirds", or to make the product entirely 35 useless and without value as hosiery. Frequently, the actual breaking of the threads at the narrowing points does not occur, or the breaking is not noticeable, or does not become apparent until the hose is finally 40 45 seamed and shaped on the boards, or possibly, until it is finally sold and worn for the first time. At any one of these stages it frequently occurs that, a weakness in the thread, or possibly, an actual break in the thread at the narrowing points, will immediately start a "run".

The object of my invention is, chiefly, to eliminate the damage caused by the frequent breaking of the thread at the narrowing 50 points, either while in the process of making or while the hose is in use, and moreover, to eliminate at the same time the unsightly row of such narrowing points on the finished product.

55 With the above ends in view, my inven-

tion consists of a method of knitting full fashioned hosiery, wherein, the number of narrowing needles at each end of the hose, that is, along each edge of the hose in the flat condition, is reduced to a minimum or 60 to a relatively low number, to wit, such a number as will bring the series of narrowing points at such close distance from the edges of the flat unseamed hose, that when such flat product is finally seamed to form 65 the finished hose, the narrowing points will be taken up, or sewed or stitched up within the seam of the hose, thereby, not only eliminating from view, the unsightly narrowing points, but also so protecting said narrowing points within the seam, that any weakness or actual break of a thread at such points will not start a run or in any way damage the hose, since such run can not 70 get outside of the seam.

75 For the purpose of illustrating my invention, I have shown in the accompanying drawings the incomplete as well as the complete product resulting from my novel method, it is to be understood however, that the various instrumentalities of which my invention consists, can be variously arranged and organized and that my invention is not limited to the precise arrangement and organization of these instrumentalities as herein 80 85 shown and described.

Referring to the drawings:—

Figure 1 represents a side elevation of a finished full fashioned hose embodying my invention.

Figure 2 represents a view of the narrowing points of the hose in the flat condition, or unseamed, embodying my invention.

Figure 3 represents a view of the narrowed portion of the hose along the seam, 95 on an enlarged scale also embodying my invention.

Referring to the drawings, in which like reference characters indicate like parts, 1 designates a full fashioned hose made by my 100 novel method, being composed of the welt 2, the body or leg portion 3 and the foot 4. The full fashioned hose, as is well known in the art, is produced upon a flat full fashioned knitting machine, wherein the hose is 105 knitted in a flat condition and is also narrowed or shaped at the same time by means of a series of narrowing needles at each edge of the flat hose form, which narrowing needles are brought into action over the por- 110

tions of the hose which are to be narrowed or shaped, indicated by the arrows 9. These narrowing needles have the effect of picking up a suitable number of stitches at the edges 5 of the hose and bringing said stitches inwardly a suitable distance, thereby effecting a narrowing to that extent. At the points where the hose is thus narrowed, the lines of 10 stitches carried by the narrowing needles converge with, and intersect the lines of stitches not affected by the narrowing needles, with the result that the distinctive narrowing points are produced where each 15 of the normal lines of stitches meet and terminate in the innermost line of narrowing stitches.

This is clearly illustrated in the drawings, with particular reference to Figure 2, showing my novel method, wherein the parallel 20 lines designated by the numeral 5 represent the lines of stitches extending longitudinally throughout the body, while the numeral 6 designates the lines of narrowing stitches adjacent to the edge of the flat hose 25 form, which are affected by the narrowing needles and are moved inwardly at suitable intervals, or with a given number of stitches by one or two or any suitable number of positions. The narrowing points, or the points 30 at which the innermost of the narrowing rows or stitches is intersected by the other rows of stitches unaffected by the narrowing needles, are designated by the numeral 7. It will be seen that by my novel method this 35 row of narrowing points 7, is moved or shifted to within but a slight distance from the edges of the flat hose form, while by the method employed heretofore this line of narrowing points was a considerable distance 40 from the edges. I accomplish the above by reducing the number of narrowing needles at each of the edges from the usual number of about eighteen to a minimum number of about two or three.

5 The result of this novel method is the production of a hose, illustrated in the figures of the drawing, wherein the narrowing points 7 are completely taken up by the seam 8 during the normal seaming operation, pro-

ducing a finished product having no narrow- 50 ing points in the body of the hose.

The advantages of my novel method and the product resulting therefrom are many fold, as brought out hereinbefore, to wit, that any weakness of the thread, or even a 55 broken thread at such narrowing points, is secured permanently by the seaming operation and thus runs due to such weaknesses or defects in the threads at the narrowing points are prevented. Furthermore, the unsightly row of narrowing points is completely eliminated from view. 60

It will now be apparent that I have devised a novel and useful method of making full fashioned hosiery and the product thereof which embodies the feature of advantage 65 enumerated as desirable in the statement of the invention and the above description, and while I have, in the present instance, shown and described a preferred embodiment thereof 70 which will give in practice satisfactory and reliable results it is to be understood that such embodiment is susceptible of modification in various particulars without departing from the spirit or scope of the invention 75 or sacrificing any of its advantages.

Having thus described my invention, what I claim as new and desire to secure by Letters Patent is:—

1. The method of making full fashioned 80 hosiery, which consists in knitting a hose in the flat condition along parallel lines, narrowing or shaping said hose along the edges thereof by shifting inwardly at suitable intervals, a relatively few of the outermost 85 stitches, thereby to position the narrowing marks a relatively small distance from the respective edges of the flat hose form, and spaced therefrom, and seaming the edges of said flat hose form so as completely to gather 90 in, within said seam, said narrowing marks.

2. A full fashioned hose comprising a flat fashioned blank having the narrowing marks in close proximity to the selvage edges thereof; said blank being sewed up along said 95 edges with the narrowing marks completely gathered within the seam produced thereby.

MAX A. MARSCHNER.
